UNITED STATES PATENT OFFICE.

CLARENCE D. PLATT, OF BRIDGEPORT, CONNECTICUT.

INCLOSED-SWITCH CONSTRUCTION.

Application filed March 12, 1921. Serial No. 451,844.

To all whom it may concern:

Be it known that I, CLARENCE D. PLATT, a citizen of the United States of America, residing at Bridgeport, Connecticut, have 5 invented a new and useful Inclosed-Switch Construction, of which the following is a specification.

My invention relates particularly to the operating handle construction and method 10 of support.

It has been customary in the past to form the operating handle and shaft of one piece of metal which is inserted into bearings in the opposite sides of the box and then bent 15 so as to bring the handle into the proper position. It is difficult to perform this operation satisfactorily and I therefore sought to so modify the construction that the operating shaft and handle may be preformed 20 and then assembled in the box at a minimum expense.

The drawing shows one form of construction embodying the improvements of my invention in which the box is of sheet metal 25 and the handle and shaft formed of a single rod bent into the proper shape and then inserted into holes in the opposite sides of the box. The handle side of the box is specially shaped at the hole therein so as to permit the 30 insertion or threading of the shaft without bending it.

Fig. 1 is a perspective view of an inclosed switch box, the cover being shown open and broken away and the handle and shaft construction in the act of being inserted in place.

Fig. 2 is an end view of the construction embodying the improvements of my invention with the interior switch mechanism and shaft shown dotted in its normal, operative 40 position.

Fig. 3 is an enlarged view of a fragment of the handle side of the box showing the form at the bearing hole.

Fig. 4 is a sectional view of the same on 45 the plane of the line 4-4 of Fig. 3.

The box 5 is preferably of sheet metal and provided with a cover 6. Any suitable form of switch indicated at 7 may be employed with movable contacts such as 8.

50 The shaft or crank construction 9 has bearing portions 10 and 11 which are seated in holes 12 and 13 in the opposite sides of the box. The handle portion 14 is integral with the remainder of the shaft and crank construction and may also be provided with an integral hand piece 15.

Adjacent the bearing hole 13, the wall of the box is indented at 16 and pressed outward at 17 so as in effect to produce an inclined entrance to accommodate the shaft 60 and crank in the act of assembly as indicated in Fig. 1.

By this construction it is possible to accurately preform the shaft with its bearing ends and crank and handle portions and 65 then insert the end 10 through the hole 13 and work the shaft back and forth into its final position as indicated in Fig. 2, the inclined passage formed by the grooved portions 16 and 17 making this possible. To insure the permanent positioning of the parts it is preferable that the parts be so proportioned that the shaft and crank portions have to be sprung somewhat in finally inserting the end 10 into the hole 12. The 70 parts may be so proportioned as to utilize the springiness of the sides of the box in the act of assembling. The hole 13 punched through the side of the box may be somewhat oval before the grooved portions 16 and 17 75 are formed so that the resultant hole provides a substantially cylindrical bearing for the part 11 of the shaft and handle construction.

The drawing shows the shaft-receiving 80 grooves 16 and 17 disposed at a substantial angle to the hole 13, which is desirable when a shaft like that in the drawing is used, but it is understood that these shafts may be bent in different ways and, in some cases, 85 it may be desirable to change the angular relations of the grooves accordingly.

Although this construction is very simple and inexpensive, it satisfactorily solves the 90 problem as herein set forth.

I claim:

1. In an inclosed switch construction, a box having bearing holes in the opposite sides, a preformed integral handle and shaft construction mounted in said bearing holes, 100 the wall of the box adjacent the hole on the handle side having an inclined groove to permit angular movement of the handle and shaft in the act of assembling the parts.

2. In an inclosed switch construction, a 105 box having a bearing hole in one wall with oppositely disposed inclined grooved portions adjacent thereto, and a preformed shaft and handle construction supported in said hole and adapted to be inserted and 110 removed through said hole substantially as described.

3. In an inclosed switch construction, a box having a hole in one wall thereof, with portions on opposite sides of said hole pressed inward and outward respectively to form an inclined passage, and a preformed shaft and handle construction supported in said hole.
4. In an inclosed switch construction, a box having bearing holes in the opposite

sides thereof, the wall of said box adjacent 10 one hole being pressed inward and outward on opposite sides thereof to form an inclined passage and an integral combined operating shaft and handle supported in said holes and insertible and removable 15 therefrom.

CLARENCE D. PLATT.
